LOADER ATTACHMENT FOR ROAD GRADERS

Joshua R. Wells, Jr., and Paul S. Winters,
Maryville, Mo.

Application June 15, 1951, Serial No. 231,683

3 Claims. (Cl. 214—131)

1

Our invention relates to improvements in loading mechanisms for road graders and is designed as an improvement over the mechanism forming the subject matter of our abandoned application for U. S. Letters Patent, Serial No. 765,824, filed August 4, 1947.

The primary object of our invention is to equip the conventional road grader with pivoted scoop carrying arms swingable forwardly and upwardly of the grader from lowered, substantially vertical, scoop loading position, into a scoop dumping position high above the grader, and to provide means for swinging the scoop carrying arms which will exert a lifting force thereon for lifting heavy loads in the scoop without overburdening the power means so as to cause injury thereto.

Another object is to provide means for accomplishing the above which is adapted for installation on the conventional road grader, without necessitating modification of the grader, and which will not get out of order under heavy duty operation, and is economical to service, and manufacture.

Other and subordinate objects, within the purview of our invention, will become readily apparent when the succeeding description and claims are read with reference to the drawings accompanying and forming part of this specification.

In said drawings:

Figure 1 is a fragmentary view in side elevation, partly in section, illustrating our invention in the preferred embodiment thereof;

Figure 2 is a fragmentary view in front elevation;

Figure 3 is a fragmentary view in plan with parts shown in section;

Figure 4 is a view in longitudinal vertical section taken on the line 4—4 of Figure 3 and drawn to a larger scale;

Figure 5 is a transverse vertical sectional view taken on the line 5—5 of Figure 4;

Figure 6 is a fragmentary view in perspective of the bumper bar and parts associated therewith;

Figure 7 is a view in horizontal section taken on the line 7—7 of Figure 1 and drawn to a larger scale;

Figure 8 is a fragmentary view in perspective of the scoop back plate and parts thereon; and

Figure 9 is a fragmentary view in side elevation illustrating the scoop inverted for use as a bulldozer blade.

Referring to the drawings by numerals, the numeral 2 designates the frame beam of a conventional road grader and which is provided

2

with a downturned front end 3 supported on the front axle housing 4 of the front steering wheels, one of which is shown at 5.

According to our invention, a pair of upright channel bars 6, 7 at opposite sides of the beam 2 are bolted at lower ends thereof, as at 8, to a supporting angle iron bar 9 bolted, as at 10, to the front end 3 of the beam 2 transversely of said end 13. A channel cross bar 11 connects the bar 6, 7, substantially centrally thereof, also upright crossed brace members 12 intermediate the ends of said bars 6, 7, a top tubular member 13 further connecting said bars 6, 7 and another tubular transverse member 14 adjacent the upper ends of said bars 6, 7 below the member 3.

The bars 6, 7 are held upright by a pair of rearwardly extending, horizontal angle bars 15 upon opposite sides of the beam 2 suitably attached at the front ends thereof to the cross bar 11, and spaced apart parallel by diagonal crossed bars 16 and a cross bar 17 intermediate the ends of said angle bars 15. The rear ends of the angle bars 15 underlie a cross plate 18 resting on the beam 2 and are connected to said plate 18 by bolts 19 extending through the ends of U-shaped clamping members 20 straddling the beam 2 and together with the bolts 19 clamping said plate 18 on said beam 2.

A pair of scoop carrying arms 21 are pivoted at upper ends thereof at the outer sides of the bars 6, 7 by means of a rod 22 extending through the tubular member 14 and through said arms 21 with retaining nuts 23 on the ends of the rod, said arms 21 being vertically swingable upwardly and forwardly of the grader from a lowered scoop loading position into an upswung scoop dumping position. Crossed braces 25 connect the arms 21 intermediate the ends thereof.

The scoop 24 carried by the scoop carrying arms 21 is provided with upwardly tapering sides 26, a flat bottom 27 inclined forwardly and downwardly in the lowered positions of said scoop for digging or picking up a load from the ground, and a back closure plate 28 hinged, as at 29, to the upper rear corners of the sides 26 to swing open downwardly and rearwardly for dumping the scoop. The scoop 24 fits between the lower ends of the scoop carrying arms 21 and is detachably secured thereto, when used as a scoop, by a series of three bolts 30 in each arm 21 spaced longitudinally thereof and extending through the sides 26, each series of bolts 30 also extending through a clamping bar 31 opposed to the inner face of each side 26 and for a particular purpose presently explained. An additional

bolt hole 32 is provided in each side 26 of the scoop 24 forwardly of the arms 21 when said arms are attached as above described, the additional bolt hole serving a purpose presently explained.

A horizontal, channeled bumper bar 33 with a resilient cushion strip 34 therein is provided to extend behind and across the scoop 24 to cushion and limit downward swinging of the scoop 24 into lowered loading position, the bumper bar 33 being adjustably attached adjacent its ends to the axle housing 4 by threaded studs 35 on said bar, similar studs 36 fixed to the axle housing 4 by clamps 37, and threaded sleeves 38 connecting said studs 35, 36 in pairs for adjusting said bar 33 forwardly and rearwardly as occasion may require. The cushion strip 34 is divided in the center of the bumper bar 33, as shown at 39 in Figure 6, to accommodate, when the scoop 24 is lowered, a draw bolt 40 for latching the back 20 plate 28 of the scoop 24 closed.

The draw bolt 40 is slidably mounted in guides 41 on the back closure plate 28 of the scoop 24 for gravitational movement when the scoop 24 is lowered, into a keeper 42 on the rear edge of the bottom 27 of the scoop 24 whereby to latch said plate 28 in closed position. A draw bolt release lever 43 is pivoted on a pintle 44 forming part of the hinge 29 and is operatively connected, as at 45, to the draw bolt 44 for upward swinging, when the scoop 24 is raised, to release said draw bolt and unlatch said plate 28. A pull cable 46 attached at one end to the release lever 43 is trained upwardly and rearwardly over a pulley 47 on the tubular member 14 from which said cable 46 extends downwardly and rearwardly for manual operation thereof at the rear end of the grader.

Operating mechanism for swinging the scoop carrying arms 21 is provided comprising the following. A rock shaft 50 is journaled transversely of the frame beam 2 in bearings 51 bolted, as at 52, on the cross plate 18, and is provided with like end crank arms 53 fast thereon for a purpose presently described. Telescopic, sectional push bar connections 54 extend forwardly from the crank arms 53, on opposite sides of the member 2, to said arms 21, each connection 54 comprising a pair of aligned rear and front push bar sections 55, 56, the rear section 55 being pivoted at its rear end, as at 57, to the adjacent crank arm 53, whereas, the front section 56 is pivoted, as at 58, to the scoop carrying arm 21 on the same side of the member 2. The rear section 55 is longitudinally slideable relative to the front section 56 in the rear end of a sleeve 59 into the front end of which the front section 56 is extended part way and fixed by a set bolt 60 for longitudinal adjustment relative to the sleeve 59, and the rear section 55, as occasion may require.

Each sleeve 59 is longitudinally slideable in a guide block 61. The guide blocks 61 are slidably mounted to the channel bars 6, 7 for guided movement vertically. For this purpose, each channel bar 6, 7 is provided with a pair of opposite, longitudinally extending and laterally spaced angle iron guides 63 suitably fixed to opposite sides of the channel bar to form with the flat side of the bar a vertically slotted guide way 64. Flanged and headed studs 65 bolted, as at 66, to the guide blocks 61 extend into the guideways 64 with the heads 67 thereof pivoting and sliding in said guideways.

The operating mechanism further includes, in addition to the foregoing, a cable wind up mecha-

nism which will now be described. The cable wind up mechanism comprises a pair of fly wheel forming plates 70 fastened upon opposite ends of the rock shaft 50 and which are preferably, 5 for reinforcing purposes, formed integrally with the crank arms 53. A pair of pull cables 71 are connected at one end thereof to said plates 70, as at 72, and are trained upwardly, upon opposite sides of the member 2 over pulleys 73 at the outer sides of said bars 6, 7, the pulleys 73 being confined by nuts 74 on a shaft 75 extending through the upper tubular member 13. From the pulleys 73, the cables 71 are trained downwardly and attached to the pivots 58 on the arms 21. Peripherally grooved cable tensioning segments 76 are provided on confronting sides of the plates 70 to engage and exert pull on the cables 71 in a manner presently described. Cable guards 77 are provided on channel bars 6, 7 over the pulleys 73.

A power drive for the rock shaft 50 is provided and which comprises a hydraulic pressure cylinder 80 extending longitudinally over the frame member 2 and bolted at its rear end, as at 81, to the beforementioned cross bar 11 with its front end fixed by a clamp 82 to the beforementioned cross bar 17. A toothed piston rod 83 extends out of the front end of the cylinder 80 and overlies and meshes with a gear pinion 24 as on the rock shaft 50 centrally thereof. The piston rod 83 is formed in two sections 85, 86 jointed, as at 87, for attachment of the section 85, which is toothed, to the section 86. A channeled hold-down guide 88 straddles the toothed section 85 and is bolted as at 89 to a pair of the bearings 51 with shim plates 90 between said guides and the bearings for adjusting the working clearance between said guide 88 and the toothed section 85. A hydraulic fluid pressure supply and release line 91 extends to the rear end of the cylinder 80 and a suitable pressure control and release valve 92 on one of the before mentioned bars 15 is connected to said line 91 and adapted for connection to a source of fluid pressure supply, not shown, in any suitable manner. A pull rod 93 for operating the valve 92 is connected to an operating lever rod 94 of said valve. A spring 95 operates the lever 94 to slide the bolt 49 downwardly.

Referring now to the operation of the invention, in the lowered position of the scoop carrying arms 21, the crank arms 53 extend downwardly and rearwardly from the rock shaft 50 and the rear push rod sections 55 abut the front push rod sections 56 in the sleeves 59, as shown in Figure 1, and the push rod connections 54 incline downwardly and forwardly to the scoop carrying arms 21 in substantially the position shown in Figure 1. Upon operation of the rock shaft 50 and crank arms 53, through substantially an eighty degree arc of movement, counter-clockwise as shown in Figure 1 by the arrow, the push rod sections 55 are moved forwardly to correspondingly move the push rod sections 56 and cause upward and forward swinging of the scoop carrying arms 21 and the scoop 24 into partially elevated position, said sections 55, 56 swinging upwardly about the pivots 57 to compensate for upward swinging of said arms 21. During upward swinging of said sections 55, 56, the sleeves 59 slide forwardly in the guide blocks 61 which slide upwardly and pivot in the guideways 64 to compensate for upward swinging of said sections 55, 56 and the sleeves 59 while retaining the sections 55, 56 aligned. At the end of substantially eighty degrees of movement of

the crank arms 53, the rod sections 55, 56 have reached substantially horizontal position, as shown by dotted lines in Figure 1, and the scoop carrying arms 21 and scoop 24 have been partly raised through a first stage of swinging movement into the position shown in dotted lines in Figure 1. During such operation of the scoop carrying arms 21, the segments 76 have merely taken up the slack in the cables 71 caused by upward swinging of the scoop carrying arms 21. When the rod sections 55, 56 have reached substantially horizontal positions, the effective thrust thereof against the scoop carrying arms 21 begins to diminish, for reasons which will be clear. At this point, and upon further operation of the 15 rock shaft 50, in the same direction, the segments 76 cause winding up of the cables 71 around the same and swing the scoop carrying arms 21 and the scoop 24 upwardly through a second stage of operation into fully raised positions, as shown by the dot and dash lines in Figure 1, the sleeves 59 sliding forwardly on the rear push bar sections 55 to compensate for forward throw of the scoop carrying arms 21 relative to the rear push bar sections 55, said sleeves sliding and pivoting in the guideways 64, for reasons which will be clear. The peripheral curvature of the segments 76, it will be understood, is compound and suitable for accomplishing the results as set forth in connection therewith. By 30 discharging the pressure from the cylinder 80, under control of the valve 92, the parts will assume normal position under the weight of the scoop carrying arms 21 and scoop 24 as will be apparent.

As shown in Figure 9, the scoop 24 may be inverted for use of the bottom thereof as a bulldozer blade. This may be accomplished by removing the two end bolts 30 of the series, and the clamping bars 31. Then swinging the scoop 24 into inverted position on the other bolts 30 at each side of said scoop and then bolting the clamping bars 31 to the scoop carrying arms 21 and to the sides 26 of the scoop 24 through the additional bolt holes 32 and two of the bolt holes, not shown, from which the bolts 30 were previously withdrawn.

As will be seen the described attachment will not interfere with normal operation of the grader but may be easily detached from the grader and replaced when desired.

The foregoing will, it is believed, suffice to impart a clear understanding of our invention, without further explanation.

Manifestly, the invention, as described, is susceptible of modification, without departing from the inventive concept, and right is herein reserved to such modifications as fall within the scope of the appended claims.

Having described our invention, what is claimed as new is:

1. Loading mechanism for use on a horizontal frame of a road grader comprising a pair of upright side bars on said frame at one end of the grader, a pair of opposite connected lift arms having upper ends pivoted to the upper ends of said bars for upward swinging from lowered pendent position, a scoop secured to said arms between the lower ends thereof, power means for swinging said arms upwardly comprising successively operating thrust and pull mechanisms, respectively, operatively connected to said arms said thrust and pull mechanisms being connected

for operation and timing of one by the other, said thrust mechanism comprising a rock shaft having cranks thereon, thrust connections pivoted to said arms and to the cranks of said shaft 5 for upward swinging with said arms and exerting upward thrust against said arms at one side of the pivot of said arms, said pull mechanism comprising a wind-up cable exerting upward pull on said arms at the opposite side of the pivot of said arms, and means on said rock shaft for winding up said cable with a delayed tensioning action, said thrust connections comprising bar sections telescopically connected for relative sliding movement idly during upward pull on said arms by said cable.

2. Loading mechanism for use on a horizontal frame of a road grader comprising a pair of upright side bars on said frame at one end of the grader, a pair of opposite connected lift arms 20 having upper ends pivoted to the upper ends of said bars for upward swinging from lowered pendent position, a scoop secured to said arms between the lower ends thereof, power means for swinging said arms upwardly comprising successively effective thrust and pull mechanisms, respectively, operatively connected to said arms, means for permanently connecting said thrust and pull mechanisms together for operation of the pull mechanism by the thrust mechanism idly during effective operation of the thrust mechanism, said thrust mechanisms comprising a rock shaft common to both said mechanisms, said pull mechanism further comprising a wind up pull cable, and a segment mounted on said shaft eccentrically for winding up said cable with a delayed action to time operation of the pull mechanism relative to operation of the thrust mechanism.

3. Loading mechanism for use on a horizontal frame of a road grader comprising a pair of upright side bars on said frame at one end of the grader, a pair of opposite connected lift arms having upper ends pivoted to the upper ends of said bars for upward swinging from lowered pendent position, a scoop secured to said arms between the lower ends thereof, power means for swinging said arms upwardly comprising successively effective thrust and pull mechanisms, respectively, operatively connected to said arms, and means permanently connecting said thrust and pull mechanisms together for operation of the pull mechanism by the thrust mechanism idly during effective operation of the thrust mechanism, said thrust mechanism comprising bar sections telescopically connected for relative sliding movement idly during upward swinging of said arms by said pull mechanism.
